(57) **CLAIM**

The ornamental design for a washing machine having image design displayed thereon, as shown and described.

DESCRIPTION

The patent or application file contains at least one drawing executed in color. Copies of this patent or patent application publication with color drawing(s) will be provided by the Office upon request and payment of the necessary fee. FIG. 1 is a top, front, perspective view of a washing machine having image design displayed thereon showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIGS. 8-10 are reference views thereof.

The broken lines shown in the drawings illustrate portions of the washing machine that form no part of the claimed design.
